LAVATORY FAUCET

Arthur Ross, 2991 W. Outer Drive, and George Manoogian, 19255 Gainsborough, both of Detroit, Mich.

Filed Feb. 6, 1961, Ser. No. 63,844

Term of patent 14 years

(Cl. D91—3)

FIG. 1 is a perspective view of a lavatory faucet embodying our new design;

FIG. 2 is a plan view thereof;

FIG. 3 is a front elevational view thereof;

FIG. 4 is a side elevational view thereof; and

FIG. 5 is a rear elevational view thereof.

The dominant features of our new design are shown in solid lines in the drawings. The parallel lines on the base of the handle member represent conventional grooves.

We claim:

The ornamental design for a lavatory faucet, as shown and described.
